United States Patent Office

Des. 203,168
Patented Dec. 14, 1965

203,168

CHAIR

Jean Paul Giacomini, York, Pa., assignor to Thonet Industries, Inc., a corporation of Delaware

Filed Feb. 11, 1965, Ser. No. 83,782

Term of patent 14 years

(Cl. D15—1)

Fig. 1

Fig. 2

Fig. 3

Fig. 4

FIG. 1 is a perspective view of a chair, viewed substantially from the front thereof and embodying my new design.

FIG. 2 is a front elevational view of the chair shown in FIG. 1.

FIG. 3 is a side elevational view of the chair shown in FIG. 1.

FIG. 4 is a rear elevational view of the chair shown in FIG. 1.

The side of the chair not shown is the same in appearance as the side shown.

I claim:

The ornamental design for a chair as shown and described.
